UNITED STATES PATENT OFFICE

2,326,253

TRANSMISSION OF SOUND AND CONVERSATION

Fred Roberts and Arthur W. Bennett,
Kansas City, Mo.

Application October 23, 1942, Serial No. 463,086

1 Claim. (Cl. 179—4)

This invention relates to a system for the transmission of talking impulses and other wave forms, such as telegraphy or power impulses, and has for its primary object the provision of means for transmitting intelligible sound either through the employment of Morse code, continental code, or the voice over land lines or similar conductors, all of which impulses are boosted by an audio amplifier forming a part of the self-contained instrument disposed at the transmitting or receiving station.

One of the primary objects of the instant invention is to provide a compact transmitting and receiving station for code, power or voice impulses, that constitutes a composite system including amplifying means common to the apparatus for transmitting code, power or voice impulses and capable of being operably associated with the apparatus in use by a system of switches.

This invention has for a yet further aim the provision of a composite system for the transmission of sound impulses of the aforementioned character having as a component part thereof, means for supplying power to the apparatus for transmitting Morse code, continental code, and speech impulses, which source of power is brought into operative relation with the selected apparatus through a unique switch system, the character of which insures the employment of the aforesaid audio amplifying apparatus to the end that code, power or speech impulses may be sent along a conducting line or lines for great distances without the necessity of using the relatively large number of parts that must now be employed when a station is equipped to transmit and/or receive impulses of the three characters aforesaid.

A yet further aim of this invention is to provide a system for the transmission of sound and conversation that has means for both transmitting and receiving telegraphic and talking impulses, and that may be manipulated to serve as a transmitter or receiver with a minimum amount of effort and the use of a relatively small group of elements.

Heretofore, it has been the commercial practice to use separate instruments for the transmission of Morse code, continental code, and speech. Even at the present time railroad systems have separate lines of communication for the transmission of code and speech impulses, and in such systems is to be found many parts, the function of all of which is found in the communicating system embodying this invention.

All the desirable qualifications of perfectly op-

erating communicating systems over which Morse and continental code may be sent and received, and over which speech may be sent and received, are found in the unitary communicator made in accordance with our invention. In addition to such qualifications, the combination of the component sub-systems within the compact communicator at one end of the transmission line or lines are capable of producing highly efficient results and of maintaining proper and adequate power at all settings of the switches and sufficient amplification properties to send the impulses of both code and speech character over long lines without auxiliary boosting.

15 The wiring diagram illustrated in the accompanying drawing, embodies one form of the invention and shows in grouped arrangement, the apparatus forming the composite system of sound and conversation where the several impulses capable of being handled by the system are impressed on a line common to both the code impulse pick-up and speech pick-up element.

Because alternating current is universally available and usually supplied through feeder lines, such as indicated by the numerals 2 and 4, conduits 6 and 8 are joined to said lines 2 and 4 and supply current to transformer 12 when switch 10 is closed. This transformer raises and rectifies the alternating current from supply lines 2 and 4 in order that proper plate and filament voltages may be impressed upon the component units of the system. Rectifier tube 14 forms a part of the power supply and conventional filter choke 16 and condensers 18 and 20 are in circuit with transformer 12 and tube 14. A bleeder resistor 22 is also in circuit to insure correct loading of the power supply unit.

25 The means for impressing telegraphy or code impulses is a part of the apparatus when assembled for use at a station and may be made relatively small and to include parts joined to the power supply by interconnecting terminals 24 and 26 with terminals 28 and 30 of the power pack.

A housing, not here fully illustrated, is preferably supplied to establish a sound chamber 32 to contain a small sound pick-up or transmitter 34 in juxtaposition to telegraph sounder 36. When the latter is operated, its sound will be picked-up by transmitter 34 as key 38 is actuated by the operator. This key 38 is removably included in circuit through the medium of a conventional jack 40 and a group of four double-throw, double-pole switches constructed for simultaneous operation and as a unit, may be mounted on the housing which contains the other

parts of this portion of the system. These switches are designated by the numerals 42, 44, 46 and 48 respectively and when manipulated, permit directing of the code impulses or the talking impulses into lines 112 or 114 for transmission to a remote point. For example, when switches 42, 44, 46 and 48 are in one position, key 38 may be used to send Morse or continental code impulses over the transmission lines, but when the switches are in the other one of the two possible positions, voice impulses may be sent by talking into receiver 121.

Amplification of all impulses occurs through the medium of the audio amplifier, which comprises tubes 50 and 52 that receive their power supply from the source above described. Connection is made between tubes 50 and 52 by suitably joining terminal 54 of the power supply with terminals 58 and 60 of tubes 50 and 52 respectively. Terminal 56 of the power unit and one terminal of each tubes 50 and 52 are grounded to complete the circuit in an obvious manner.

An input transformer 62 is joined to tube 50 through the medium of potentiometer 64 and an output transformer 66 joined to tube 52 is inserted to control the volume of current to the transmission lines and to match the impedance to those lines. Headphones, not here shown, may be connected to this amplifying unit by a phone jack 68.

Tubes 50 and 52 having resistors and condensers necessary for their proper operation, all of which are understandably illustrated in the drawing and will not here be further described for their function and presence in an audio amplifier is well-known in the art. This amplifying unit is connected with switches 42, 44, 46 or 48 as the case may be, to insure the boosting or amplifying of impulses when they are sent over the system regardless of whether they be of the Morse, continental codes, or speech type.

The manner in which each position of the said switches is related to the sending of code or speech impulses is above described. When continental code, in the nature of telegraphy or power impulses is being used, the remaining parts of the system illustrated are brought into play. A pre-amplifier tube 70 and a rectifier and amplifier tube 72 are in circuit as shown, and are combined with an AC line voltage dropping resistor 74, choke 76, and condensers 78 and 80. Condensers 82, 84, 86 and 88 are of the fixed type while resistors 90, 92, 94, 96, 98, 100 and 102 combine with choke 104 for the intended operation of the unit and with transformer 106 for the matching of the circuit. Key 38 is used when this unit is being employed for the sending of continental code.

Switch 10 is closed to connect the system to supply lines 2 and 4. Pilot light 108 serves to visibly indicate to the operator that the system is joined to a source of current supply.

Switch 110 is known in the art as a "break-in" switch and is manipulated by the operator to change transmission lines 112 or 114 when the receiving operator at the remote end of the said lines interrupts for some reason, such as to request a repeat. Speaker 116 delivers the message from the operator at the remote end of the transmission lines to the operator near this speaker when the remote operator breaks-in to signal back. The matching transformer 118 is necessary to the operation of speaker 116.

The four double pole, double throw switches 120, 122, 124 and 126 have two positions. In one position, the receiver 127 is cut into the system for use as a receiver of talking impulses while in the other position, the receiver 127 becomes a speaker through which the operator hears spoken words coming from a remote point over the transmission lines leading to the instrument. Transformer 128 is necessary in matching.

The switching system shown insures that the impulses leaving the system are all boosted or amplified for distance.

The illustrated embodiment of the invention is schematically shown and since it is realized that circuits having different characteristics and substitute parts may be employed to accomplish the broad objects of this invention, it is desired to be limited only by the scope of the appended claim.

Having thus described the invention, what is claimed as new and desired to be secured by Letters Patent is:

In a composite system for the transmission of talking impulses, telegraphy impulses and power impulses over a common conducting line, means for impressing talking impulses on the said line; means for impressing telegraphy impulses on the said line; means for impressing power impulses on the said line; an audio-amplifier for boosting the particular impulse passing over said line; a switching system for selecting and associating either the means for impressing talking impulses, the means for impressing the telegraphy impulses or the means for impressing the power impulses on the said line; and a power supply unit for the said several impulse impressing means, the said switching system being adapted to supply current to the selected impulse impressing means from said power supply unit.
